ATTACHMENT FOR CIGAR LIGHTERS, TROUBLE LAMPS, ETC

Filed May 19, 1924

UNITED STATES PATENT OFFICE.

CHARLES H. CUNO, OF MERIDEN, CONNECTICUT, ASSIGNOR TO THE CUNO ENGINEERING CORPORATION, OF MERIDEN, CONNECTICUT, A CORPORATION OF CONNECTICUT.

ATTACHMENT FOR CIGAR LIGHTERS, TROUBLE LAMPS, ETC.

Application filed May 19, 1924. Serial No. 714,314.

My invention relates particularly to means for mounting an electric "cigar lighter" or "trouble lamp". Such devices usually consist of a casing containing a spring operated drum for the current carrying cord such as shown for instance in the Cuno Patents 1,208,504, 1,342,015, 1,355,943 and 1,378,013. Ordinarily these devices are secured to the back of the instrument board or cowl through which a hole is cut for the cigar lighter or lamp as the case may be. Such installations require considerable time and skill as well as suitable drilling or cutting devices. I have therefore sought to provide a simple and inexpensive means by which the apparatus may be quickly and easily mounted by anyone and requiring no tools except a wrench and screw driver.

To carry out this invention I provide a casing with a tubular extension on which is mounted a U shaped frame adapted to be readily clamped to the lower edge of the instrument board or cowl. The parts are so constructed that this frame may be detached if desired and the apparatus mounted in the usual manner at the back of the instrument board with its tubular member extending through the board.

Fig. 1 is a side view showing a cigar lighter with the attachment of my invention as applied to a metal cowl or instrument board.

Fig. 2 shows the device without the attachment as applied to a wooden or solid board.

Fig. 3 is an exploded perspective view showing the parts of a cable winding device with the attachment.

The casing 5 may be of any suitable design and construction and containing the spring driven winding drum or reel 6 for the conductor cords or cable 7 leading to a current consuming or translating device 8 such as a cigar lighter or lamp.

The casing is provided with a tubular extension 9 which is secured in place at the front edge of the casing by spinning or flanging the inner end of the tube as shown at 10 around the rear edge of an opening in the face plate 11 of the casing. The outer end of this tube 9 serves as an abutment for a shoulder on the translating device to limit the inward movement thereof.

The U shaped clamping frame is preferably made of sheet metal blanked and bent

into the desired form and consists of a front plate 12, a rear plate 13 and a bottom spacing member 14. These plates 12 and 13 are provided with openings 15 and 16 respectively so that the frame can be readily slipped on over the tube 9 into the position shown in Fig. 1. The front and back plates 12 and 13 are spaced apart a distance corresponding with the maximum thickness of instrument boards commonly used on standard cars. The attachment frame is secured on the tube 9 in any suitable manner such as for instance as by means of a nut 17 screwed on to the threaded end of the tube. Preferably washer 18 is interposed between the nut and the front plate 12 of the clamp frame. Said screws 19 are seated in the upper outer edges of the rear clamp plate 13 and adapted to be adjusted against the rear face of the instrument board or cowl. In Fig. 1 I have shown a metal board 20 which usually has a rearwardly extending flange 21. I therefore locate the set screws 19 sufficiently above the opening 16 so as to permit the screws to clear the rear edge or flange 21 of the board when the parts are assembled. This flange 21 is thus located between the screws 19 and the tube 9. This makes it possible to loosely hook the device to the lower edge of the flange on the instrument board before permanently securing it in place. The device can thus be adjusted laterally to the exact position desired after the wiring has been completed. It will also be noted that the clamping frame is somewhat wider than the thickness of the casing 5 so that the rear ends of the screws 19 extend along the flat sides of the casing. This holds the clamping frame on the tube 9 from rotation even before the parts are clamped together by the nut 17.

In Fig. 2 I have illustrated the cable winding device applied to a solid instrument board 22 and without the U shaped clamping attachment. This is made possible because the clamping adjustment is detachable and the tube 9 and nut 17 are adapted to clamp the device directly to the board 22. This figure also shows the usual hole 23 cut through the board. In this case the hole 23 is made large enough to accommodate the tube 9.

According to this invention it is possible to supply the U shaped clamping frame with the reel or as a separate attachment which

can be used or not as desired. It will also be seen that the construction may be installed by anyone in the position in Fig. 1 with very little trouble in a few moments. 5 Later if the owner of the car desires to have the device attached as shown in Fig. 2 when he has sufficient time or can procure the services of some one sufficiently skilled to mount it, then in that event the U shaped 10 clamping frame may be discarded.

While I have shown the clamping frame in what seems to me to be its simplest and preferred form it should be understood that I anticipate that changes of details and in 15 design may be made without departing from the spirit of my invention.

I claim:

1. A detachable clamping member for a cigar lighter comprising a one-piece 20 U shaped frame having openings in its opposite sides in alignment with each other and adapted to receive a tubular extension of a reel casing and set screws in the upper edge of the rear of the frame spaced apart 25 from each other so as to extend alongside of the opposite sides of a reel casing when said member is applied to the front edge thereof.
2. A casing containing a reel, a tubular extension secured directly to said casing and 30 having a screw threaded outer end, a power consuming device fitting in the outer end of said tubular extension, a conductor cord con-

necting said device and said reel and passing through said tubular extension when said device is drawn out, a U-shaped clamp 35 removably mounted on said tubular extension and adapted to engage the lower edge of an instrument board, a nut adjustable on the screw threaded outer end of said extension for detachably holding said clamp on said extension and a set screw passing through one arm of said clamp from the rear and adapted to engage the rear of the instrument board.

3. A cigar lighter comprising a reel casing, a tubular outlet member for the cord, the inner end of the outlet member being permanently secured to the casing and the outer end of the outlet member having a 45 screw threaded portion, means for clamping said casing and its outlet member to the lower edge of an instrument board comprising a flanged member detachably mounted on the tubular outlet member to engage the front of the board and a clamping screw mounted in the rear of the flanged member to coact with the rear of the instrument board and a nut adjustable on the screw threaded outer end of the tubular 50 outlet member for holding the casing and its outlet member on the board with the clamping means or without it.

CHARLES H. CUNO.
